UNITED STATES PATENT OFFICE

GEORGE O. LARBERG, OF KANSAS CITY, MISSOURI, ASSIGNOR TO AUTO MOP MANUFACTURING COMPANY, OF KANSAS CITY, MISSOURI, A CORPORATION OF MISSOURI

MOP

Application filed March 7, 1932. Serial No. 597,313.

My invention relates to improvements in mops. It is particularly well adapted for washing automobiles.

One of the objects of my invention is to provide the head of a mop of the kind described with novel means for covering with soft material all portions of the head which are adapted in the use of the mop to contact with the surface which is being washed, and thus eliminate liability of scratching such surface.

A further object of my invention is to provide novel and efficient means for fastening the mop to the mop head, which is simple, cheap, strong, durable, not likely to get out of order, and which enables the quick and easy attachment of the mop to the head.

The novel features of my invention are hereinafter fully described and claimed.

In the accompanying drawing which illustrates the preferred embodiment of my invention and a modification thereof,

Fig. 1 is a plan view of a mop head provided with my improvement.

Fig. 2 is an enlarged section on the line 2—2 of Fig. 1.

Fig. 3 is an elevation, partly broken away of the mop head shown in Fig. 2.

Fig. 4 is a plan view, partly broken away, of the mop head looking at the bottom thereof, the outer mop being omitted.

Fig. 5 is a sectional fragmental view of a modification which employs but a single mop.

Similar characters of reference designate similar parts in the different views.

1 designates the top of a cuplike mop head provided with a discharge opening 2, Fig. 4, which communicates with a tubular stem 3 adapted for attachment to a hose, not shown.

The mop head is provided with a depending wall 4 provided on its inner side near its top with a circumferential groove 5. The outer side of the wall 4 is provided, below the groove 5 with a circumferential groove 6.

In the form shown in Fig. 2, two mops 7 are shown respectively supported by two pieces of relatively soft sheet material 8 and 9 which respectively extend around and embrace the inner and outer sides of the wall 4

and cover the lower edge of the wall, said two pieces being sewed together below said edge, so as to be in effect one sheet.

The inner piece 8 embraces a securing member comprising an expandable and contractible resilient wire divided ring 10, Figs. 2 and 4, which is retained in the inner groove 5 by its resiliency and expansibility, and which firmly holds the sheet material 8 against the inner side of the wall 4.

For holding the outer piece of sheet material 9 against the outer side of the wall 4, securing means located in the outer groove 6 is provided, and, as shown, comprises a wire 11 having its ends fastened together, Fig. 3, and located in the outer groove 6 in which it engages and holds in said groove the outer piece 9 of sheet material.

In the form shown in Fig. 5, the parts correspond to the form shown in Figs. 1 to 4, excepting that but a single mop 7 is employed and the sheet material supporting the mop comprises but a single piece 12 which covers the inner and outer sides and the lower edge of the mop head 4, said piece 12 covering the expansive divided ring 10 and being held by said ring in the inner groove 5, and being held by the wire 11 in the outer groove 6 of the mop head 4.

As both sides and lower edge of the mop head are covered by the soft sheet material 8, in the form shown in Fig. 2 and by the soft sheet material 12 in the form shown in Fig. 5, there is no liability of the mop head scratching the surface washed.

I do not limit my invention to the structures shown and described, as many other modifications, within the scope of the appended claims, may be made without departing from the spirit of my invention.

What I claim is:

1. In a mop, an inverted cup-shaped head the depending wall of which is provided with two grooves extending circumferentially around its inner and outer sides respectively, mop supporting relatively soft sheet material covering the inner and outer sides and the lower edge of said wall, an expandable resilient member embraced by and holding said ma- 100

terial in said inner groove, and means for holding said material in said outer groove.

2. In a mop, a head having a peripheral depending wall provided around its inner and outer sides respectively with a circumferential groove, a mop supporting relatively soft sheet material covering the inner and outer sides and the lower edge of said wall, a resilient expansible and contractible member holding said material in said inner groove and retained therein by its resiliency, and means for holding said material against the outer side of said wall and in said outer groove.

In testimony whereof I affix my signature.

15 GEORGE O. LARBERG.
